Inventor:
WILSON R. ELLIS
Victor J. Evans
attorney.

UNITED STATES PATENT OFFICE.

WILSON R. ELLIS, OF BERKELEY, CALIFORNIA.

AGITATOR.

Application filed September 10, 1926. Serial No. 134,744.

This invention relates to agitators and has particular reference to a simply constructed household article of the character described which embodies in its mechanism an agitating element adapted to be manually actuated so as to thoroughly whip or beat eggs, cream or the like in a minimum amount of time.

The subject matter of the present invention is in the nature of an improvement upon the agitator forming the subject matter of my copending application, Serial No. 111,362, filed May 24, 1926.

The object of the present invention is to improve and simplify the mechanism of the parent invention, and to reduce the cost of its manufacture, without changing its mechanical action or impairing its efficiency.

Other objects and advantages will be apparent during the course of the following description.

In the accompanying drawings forming a part of this specification and in which like numerals are employed to designate like parts throughout the same,

25 Figure 1 is a rear elevation of my improved agitator, a portion of the mechanism being broken away to better illustrate the same,

30 Figure 2 is a side elevation of the invention, the view being taken at right angles to Figure 1,

Figure 3 is a bottom plan view of the beater element and base, and

35 Figure 4 is a detail view of the shaft and its associated parts forming part of my invention,

Figure 5 discloses a modified form of universal joint construction and associated mechanism for the preferred form disclosed 40 in Figures 1, 2 and 4.

In the accompanying drawings wherein for the purpose of illustration is shown a preferred embodiment of my invention, the numeral 5 designates a handle having secured thereto a downwardly extending shank 6. Rotatably mounted on this shank is a gear wheel 7, equipped with a handle 8, which handle serves as a means for the manual rotation of the gear wheel 7.

45 50 As illustrated to advantage in Figure 2, the shank 6 is so constructed that it provides bearings 9 and 10 for receiving therein and rotatably supporting a shaft 11. Adapted to mesh with the gear 7 is a spur gear 12 which is rigidly fixed upon the shaft 11 below the bearing 10.

It will be observed that the shaft 11 is bent near its lower extremity to form an offset arm 12 and is then bent at an angle to the offset arm 12 to provide an eccentric 60 shaft 13 which is rotatably pivoted in a bearing 13' in a base support 14. The said base support 14 has flexible arms 14' and is slightly convexed so that they will readily adapt themselves to bowls of various shapes 65 and sizes.

The numeral 15 designates a collar secured to the lower end of the shaft 13 and serves to retain the base plate 14 in a bearing 15' on the shaft 13.

70 As illustrated to advantage in Figures 1, 2 and 3, the numeral 16 designates a beater element which is substantially semi-spherical in shape, and is perforated as at 17 to provide a plurality of circular openings in the walls thereof. A bearing 13' is provided at the center of the beater 16, at a point corresponding to the pole of the semi-sphere.

75 The numeral 18 indicates a cross bar or bridge which is secured at its extremities near the top of the inner wall of the beater element 16, on a line through its diameter, and is adapted to provide a central and upper bearing 18' for the eccentric shaft 13. The referred to bearings 13' and 18' permit 80 the eccentric shaft 13 to rotate within the bearings of the beater element 16, while a collar 20 on the shaft 13 confines the vertical movement of the beater element 16 on the eccentric shaft 13.

85 The base 14 is provided with a plurality of upwardly extending teeth 21 adapted to be received in and mesh with the series of perforations 17, etc., formed in an orbit near the axis of the beater element 16.

90 In operation the eccentric shaft 13, being manually rotated by means of gear wheel 7, will swing on its bearing at an angle and carry the beater element 16 with it, but as the said eccentric shaft 13 is loosely journaled in the beater element 16, and since said beater element is positively geared to the base support 14, a substantial universal joint connection is established, and the same mechanical movement of the beater element 16 100 results, as in my former and co-pending application.

105 110 As disclosed to advantage in Figure 5, I have illustrated a modified form of universal joint construction and associated mechanism wherein the numeral 22 designates a sleeve fixed on the shaft 23, which shaft terminates

above the lower extremity of the sleeve, while a stub shaft 24 is secured to the beater element 16.

Between the top of the stub shaft and the lower extremity of the sleeve 23 a ball bearing 25 is positioned in a ball race 26.

Connected to the stub shaft is a link element 27 which engages a second link element 28 carried by the base support 14. 10 On the base support, in the present construction, I have eliminated the teeth 21 and have found that the modified form herewith disclosed is most efficacious for accomplishing the desired whipping action.

15 As stated in my former application, this universal joint connection or any substitute therefor, such as shown in this present invention may be dispensed with, permitting the material acted upon to restrain the 20 revolutions of the beater element 13; but practically such restraint is only partial. The resulting motion of the beater element 13, without a positive universal joint control, is wave-like or undulating, and is not the 25 perfect whipping aerating movement secured by the mechanism described in my former and my present application.

But I wish to claim protection for my invention when the construction eliminates 30 said fixed connection of the universal joint, as in my former application, or of any mechanical substitute therefor. For it is obvious that the frictional resistance offered by the material beaten, together with the 35 frictional resistance offered by the contact of the underside of the beater element 16 with the bottom and sides of the dish or container will operate with clutch-like effect upon the beater element 16, and retard its 40 revolution with shaft 13 so that the resulting action of the beater is very efficacious for certain purpose such, as mixing batter, whipping cream, mayonnaise, etc.

While I have shown a device which is to 45 be manually actuated, nevertheless, it is to be understood that a power shaft may be connected to the shaft 11 and the mechanism may be supported by a frame exterior to the bowl in which the material is beaten.

50 It is to be understood that the form of my invention herewith shown and described is to be taken as a preferred example of the same, and that various changes relative to the material, shape, size, and arrangement 55 of parts may be resorted to without departing from the spirit of the invention or the scope of the subjoined claims.

Having thus described my invention, I claim:—

60 1. An agitator comprising a main shaft, gear mechanism connected to said shaft for rotating the same, a beater element offset with relation to said shaft, a base plate carried by said shaft, and a universal joint

connection between said base plate and said beater element.

2. An agitator comprising a main shaft, gear mechanism connected to said shaft for rotating the same, a perforated beater element offset with relation to said shaft, a 70 base plate carried by said shaft and a universal joint connection between said base plate and said beater element, said base plate being provided with a plurality of teeth receivable in certain of the perforations of 75 said beater element.

3. An agitator comprising a main shaft, gear mechanism for rotating said shaft, a base plate carried on the lower extremity of said shaft and having a plurality of teeth 80 thereon, a perforated beater element fixed on said shaft and rotatable therewith and adapted to receive in certain of the perforations thereof the teeth of the base plate and a universal joint connection between 85 said base plate and said beater element.

4. An agitator comprising a main shaft, gear mechanism for rotating said shaft, a base plate carried on the lower extremity of said shaft and having a plurality of teeth 90 thereon, a perforated beater element fixed on said shaft and rotatable therewith and adapted to receive in certain of the perforations thereof the teeth of the base plate, and a universal joint connection between 95 said base plate and said beater element.

5. An agitator comprising a main shaft 100 offset adjacent its lower extremity to provide an eccentric shaft, gear mechanism for rotating said eccentric shaft, a base plate positioned on the lower extremity of said shaft, a beater element carried on the eccentric shaft and rotatable therewith and interposed between the offset of the main shaft and said baseplate, and a universal joint connection between said plate and said beater element.

6. An agitator comprising a main shaft 105 offset adjacent its lower extremity to provide an eccentric shaft, gear mechanism for rotating said eccentric shaft, a base plate positioned on the lower extremity of said shaft, a beater element carried on the eccentric shaft and rotatable therewith and interposed between the offset of the main shaft and said base plate, a universal joint connection between said plate and said beater element, said plate having teeth 110

thereon receivable in certain of the perforations of the beater element, and means for retaining said beater element on said eccentric shaft.

In testimony whereof I affix my signature.

WILSON R. ELLIS
